UNITED STATES PATENT OFFICE.

KNUT JONAS ELIAS HESSELMAN, OF STOCKHOLM, SWEDEN.

WATER-COOLED INTERNAL-COMBUSTION ENGINE.

1,072,946.

Specification of Letters Patent.

Patented Sept. 9, 1913.

Application filed March 8, 1912. Serial No. 682,400.

To all whom it may concern:

Be it known that I, KNUT JONAS ELIAS HESSELMAN, a citizen of the Kingdom of Sweden, residing at Stockholm, Sweden, have invented new and useful Improvements in Water-Cooled Internal-Combustion Engines, of which the following is a specification.

This invention relates to improvements in water-cooled internal combustion engines.

Experience has proved that when the wall thickness of the cylinder of an internal combustion engine exceeds a certain amount the cooling of the cylinder walls becomes insufficient. The inner parts of the cylinder wall which are subjected directly to the heat of combustion attained an essentially higher temperature than the outer parts of the cylinder wall which are in direct contact with the cooling water. The difference of temperature causes in the material stresses which when said difference reaches a certain limit can act ruinously on the same.

The object of the present invention is to provide a cooling arrangement which will render it possible to increase the wall thickness of the cylinder and thus the size of the latter while maintaining a sufficient cooling of the inner cylinder surface.

The invention consists, briefly, in the provision in the portion of the cylinder wall located inside the usual water jacket of a number of holes or channels forming passages for the cooling water and placed sufficiently near the inner cylinder surface to effect a sufficient cooling of the latter.

In the accompanying drawing I have shown two embodiments of the invention.

Figure 1 shows a longitudinal section of a motor cylinder and Fig. 2 a cross-section on line A—B of Fig. 1. Figs. 3 and 4 show a part of another motor cylinder in longitudinal section and cross-section on line C—D of Fig. 3 respectively.

Referring to Figs. 1 and 2, the motor cylinder consists of an inner mantle 1 and an outer mantle 2 which form between them a water space, and of a head 3 having a wa-

ter chamber. The upper part of the inner mantle 1 has a wall thickness otherwise not permissible and is according to the present invention provided with longitudinal holes or channels 4 through which a part of the cooling water flows from the space between the mantles 1 and 2 to the water chamber 5 of the head 3. The other part of the cooling water flows into the head 3 through the usual openings between the chamber thereof and the water space between the mantles, said openings being not shown in the drawing. The holes or channels 4 which may be made for instance by casting or boring are located sufficiently near the inner surface of the mantle 1 to cool the same.

Referring to Figs. 3 and 4, the channels 4 are formed by grooves provided in the outer side of the upper reinforced part of the mantle 1. The ribs between said grooves fit tightly in the upper end of the outer mantle 2. Though in the forms shown in the drawing only the upper portion of the inner mantle which is subjected to the highest pressure are assumed to have a wall thickness which is larger than that allowed in usual water cooled engines and the channels or passages 4 on account thereof are provided only in the said mantle portion, it is obvious that if necessary the whole mantle wall may have a wall thickness otherwise not allowed, in which case the channels or passages 4 may extend along the whole length of the cylinder.

Having now described my invention, what I claim as new and desire to secure by Letters Patent is:

An internal combustion engine cylinder having a water chamber in its head, and inner and outer walls forming between them a water jacket, and also having on the outer side of the portion of the inner wall adjacent the water chamber an increased thickness that extends into the water jacket and is there separated by an intervening space from the inner side of the outer jacket wall, and further having in said portion of increased thickness and extending throughout

the length thereof a series of passages arranged intermediate of and in communication with the chamber in the head and the water jacket between the inner and outer walls; the said series of passages surrounding the interior of the cylinder.

In testimony that I claim the foregoing

as my invention, I have signed my name in presence of two subscribing witnesses.

KNUT JONAS ELIAS HESSELMAN.
